METALLURGICAL FURNACE

Albin G. Witting, Gary, Ind.

Application May 20, 1938, Serial No. 209,127

6 Claims. (Cl. 263—6)

This invention relates to furnaces and more particularly to rail treatment furnaces. In rail treatment furnaces, particularly of the elongated roller bottom type adapted to heat-treat elongated steel articles such as rails, rods, bars and the like, the length of the furnace is adapted to enclose several such articles in end spaced relation and the width of the furnace is adapted to enclose several such articles in side spaced relation. 10 In such furnaces it is customary to periodically feed several side spaced articles at a time into the furnace at the front end of the furnace, to advance each group of articles periodically within the furnace while feeding in the succeeding groups until the furnace is completely filled and to thereafter simultaneously discharge a group from the rear end of the furnace when feeding a group in the front end. It is customary also to provide means to supply heat energy to the furnace over substantially the entire length, as for example, by means of gaseous or liquid fuel burners spaced alternately in opposite side walls of the furnace. 20

Due to the periodic opening of the furnace doors it is exceedingly difficult to maintain the furnace section adjacent each end at desired operating temperatures. It is also difficult to exhaust gases of combustion from the furnace without disturbing the desired thermal condition in the furnace. Moreover, furnace structures heretofore proposed have not been flexible as to heat treatment processes which may be practiced therein, most structures being designed for one specific process and being incapable of ready conversion to another process. Another deleterious feature of prior art furnaces is that no provision is made for rapidly cooling down the furnace in the event of shutdown or during such cooling to protect the interior of the furnace from the deleterious effects of oxidation during the cooling period.

One of the objects of the present invention is to provide an elongated roller bottom furnace structure which is substantially free from the above noted deleterious features. Another object is to provide an elongated furnace structure in which the heating and gas exhaust means co-operate in such manner that the thermal condition within the furnace from end to end is flexible and regulatable within relatively wide limits. Still another object of this invention is to provide 50 means to exhaust gases from the interior of the furnace at either or both ends or to proportionately distribute the gases exhausted at either end and to further provide means co-operatively assembled with said exhaust means to exhaust said gases from one end only, when operation of the

furnace is suspended, and to cool the exhausted gases and to feed the cooled gases into the opposite end under pressure greater than atmospheric pressures thereby to accelerate the cooling of the furnace and to prevent the access of atmospheric gases to the furnace interior.

Other objects and advantages will be apparent as the invention is more fully disclosed.

In accordance with these objects, the furnace and associated means as hereinafter disclosed, has 10 been devised. Before disclosing the same, reference should be made to the accompanying drawings, wherein—

Fig. 1 is a side elevational view partly in section of the furnace and associated means of the present invention; Fig. 2 is a top plan view of the same also partly in section; Fig. 3 is an enlarged elevational view in section of the same; Fig. 4 is an enlarged cross-sectional view of the same; Fig. 5 is an enlarged plan of one of the associated means 20 of the present invention; Fig. 6 is an enlarged section of the said associated means of Fig. 5; and Fig. 7 is a second enlarged section of the same means of Fig. 5.

Referring to the drawings, the present invention consists of an elongated furnace 1, rectangular in section, provided with a roller bottom 2 and with means 3 to drive the said bottom to move rails 4 disposed on said roller bottom 2 by feed table 5, lengthwise through the furnace from inlet end 6 to outlet end 7 and onto delivery table 8. The opposite side walls 9—9' of furnace 1 are provided with a plurality of fluid fuel burners 10 arranged in alternate sequence substantially as indicated, and means 11 is provided to supply each said burner 10 with a regulated mixture of fluid fuel (gaseous or liquid) and air, so that the heat energy output of each burner 10 may be adjusted to a desired amount for the purpose of heating the furnace section affected thereby to 40 a desired temperature. The means per se, not being a part of the present invention, will not be further described.

Along the roof of furnace 1, I provide a plurality of fans 13 with associated means 14 for driving 45 the said fans 13, whereby a downward circulation of the gases of combustion from burners 10 upon roller bottom 2 and rails 4 may be maintained. As may be noted roller bottom 2 is located in spaced relation to the usual refractory bottom 15 of furnace 1 providing a channel lengthwise of the furnace 1 for the circulation of the heated gases lengthwise of the furnace 1. Adjacent each end of the furnace 1 and in the bottom 15 of the furnace, I provide gas outlet

openings communicating with underground flues 16 and 17 leading ultimately to stack 18. In each flue 16—17 I provide damper means 19—19' to regulate the amount of gases to be exhausted through each flue from furnace 1 into stack 18. The total draft of stack 18 to be divided by the flues 16—17 is regulated by means of damper 20. Flues 16—17 join together prior to passing through damper 20 into stack 18 but after the 10 gases pass through damper means 19—19'.

This arrangement of flues and dampers enables me to regulate the amount of gases drawn from the furnace at each end and the capacity of each flue is adapted to take all the gases from the furnace or any portion of the gases as may be desired. By so regulating the draft to each flue, I am enabled to regulate the temperature differential at each end of the furnace or the drop in temperature at each end incident to the 15 feeding of relatively cold rails through the inlet opening 6 and hot rails out of outlet opening 7.

In the practice of the rail treatment method described and claimed in Brunner Patent Re. No. 19,884, dated March 10, 1936, the rails are 20 allowed to cool on a hot bed in freely moving air from the finishing rolling temperature down through the transformation temperature and to undergo transformation from austenite into ferritic structures other than martensite. The rails 25 are then reheated to a temperature slightly above the so-called upper critical temperature (at which the ferritic structures transform into austenite again) and thereafter are allowed to cool normally or by regulated rates to atmospheric temperatures. This reheating and cooling in accordance with the Brunner method is for the purpose of refining the grain size of the ferritic structure ultimately obtained, it being one of the 30 various ways heretofore proposed to overcome the deleterious effects of internal stresses and strains and the development of internal cracks and fissures incident to the said stresses and strains. The furnace of the present invention is adapted to accomplish the reheating of the rails 35 to above the upper critical temperature, preparatory to the second cooling step of the Brunner process.

It is essential in the practice of the Brunner method that each rail treated be subjected to 40 substantially identical heating and cooling conditions so that uniformity of product as to grain structure and physical characteristics be maintained as between the treated rails.

In the practice of the Brunner method in the 45 furnace of the present invention, a plurality of parallel spaced rails 4 forming a batch or group are fed endwise into the furnace from feed table 5 through inlet opening 6 which opening is then closed to the atmosphere. After a determined 50 time interval the batch of rails is moved lengthwise within the furnace approximately a rail length and a second batch introduced within the furnace. The length of the furnace is sufficient to provide for the locating of a plurality (7 or 8) 55 of these said batches of rails in end to end spaced relation therein, and ultimately when one batch is fed into the furnace, the batch adjacent the outlet end 7 of the furnace is fed out upon delivery table 8.

60 In accordance with the Brunner method, the discharged batch should have a temperature approximating but above the upper critical temperature of the steel composition comprising the rail. This temperature varies somewhat with 65 variations in steel composition, but in general

may be said to be in the range 660° to 685° C. Accordingly, the heating of the furnace by burners 10 is regulated to maintain furnace temperatures within this range at the outlet opening 7 and through the greater portion of the length 5 towards the inlet opening 6. The draft regulation in flues 16—17 is adapted to draw such a proportion of heated gases through flue 16 opening into the furnace bottom 15 adjacent the outlet opening 7 of furnace 1 as will insure the maintenance of a temperature within this range at the said outlet opening, the balance of the said gases being drawn off by flue 17 opening into the furnace bottom 15 adjacent the inlet opening 6 of furnace 1. 10 15

The temperatures in the furnace section next adjacent inlet opening 6 preferably should be as closely approximate the desired range (660—685° C.) as possible, which is exceedingly difficult to obtain in practice because of the intermittent feeding of relatively cold rails into this end of the furnace. However, temperatures not over 60° to 100° C. lower than the average range desired may be maintained in this section by proper regulation of the heat energy input to this section and by care in feeding rails of relatively uniform and identical temperatures successively into the furnace. The preferred temperature of the rail prior to feeding into the furnace is within the range 500° C. to 700° C. although any temperature within the range 300° to 700° C. may be used. 20 25 30

Referring now more specifically to the means illustrated in enlarged detail in Figs. 5 to 7 inclusive, I have provided by the arrangement 35 shown, a means to rapidly cool the interior of the furnace 1 without deleterious results to the interior of the furnace when desired. This means briefly comprises means to shut off the flues 16 and 17 from the stack 18 and means to draw the 40 gases of combustion remaining in the furnace after burners 10 have been shut off) from one end of the furnace through one flue (16) thence through a cooling means, and thence under pressures greater than atmospheric pressure back 45 into the furnace to recirculate the cooled gases therethrough. In this manner the interior of the furnace may be rapidly cooled by the cooled non-oxidizing gases of combustion to temperatures at which it is safe to expose the interior 50 of the furnace to atmospheric gases.

As indicated in Fig. 5, I provide a by-pass conduit 21 between flues 16 and 17 on the furnace side of damper means 19 and 19' therein; and provide a blower fan means 22 to create the 55 draft or pressure necessary to draw the gases from furnace 1 into flue 16, through the by-pass conduit 21 through the cooling means 23 and thence through valve 24 into flue 17 and back to the furnace. 60

Valve shut-off means 24 is provided in conduit 17 to isolate flues 16 and 17 from each other during normal operation of the furnace. When the furnace is shut down and dampers 19 and 19' are closed, valve shut-off means 24 is moved 65 to open position before recirculation and cooling of furnace gases is initiated.

It is obvious from the brief description of this means, that the specific means employed may be widely varied without departing from the 70 broad inventive idea. In Figs. 6 and 7 I have illustrated in detail one arrangement that has proven satisfactory. Fig. 6 is a sectional view taken along plane 6—6 of Fig. 5 and Fig. 7 is a sectional view along plane 7—7 of Fig. 5. 75

In the arrangement shown, cooling means 23 is a rectangular box with double walls at the smaller ends forming a chamber at each said end. A plurality of horizontal tubes 25 disposed interiorly of the box connect the two chambers together so that water may be supplied to one end chamber, pass through the tubes into the opposite chamber and drain from the said opposite chamber into a discharge pipe. 5 The top and bottom of the box 23 is open in between the opposite end chambers and the bypass conduit 21 conducts gases from flue 16 to the said open bottom. Fan means 22 closes the open top of the box and exhausts cooled 10 gases from the box through mushroom valve 24 into flue 17 when valve 24 is in open position, as indicated by arrows in Fig. 6.

I have shown dampers 19, 19' and 20 as hand operated slide dampers, counter-weighted for 20 convenience in operation but other types and kinds of dampers effective to shut off flues 16 and 17 from the draft in stack 18 would be just as satisfactory for the purposes of the present invention.

25 The advantages of the furnace cooling means above described may be recognized by those skilled in the art. In general, the operating temperatures of the furnace approximate 1600° F. The interior of the furnace is lined with insulating material of relatively low heat capacity but the roller bottom is comprised of alloy steel rollers having a relatively high heat capacity, and the steel composition employed in these rollers is deleteriously affected by oxidation, superficially and internally. It is essential therefore to protect the rollers from oxidation until the roller temperatures are at least below 800 to 900° F. During the period of cooling from 1600° F. to 800° F. the rollers must also be kept 40 rotating to prevent sagging or distortion incident to the cooling. The normal cooling time to this temperature where heat loss by radiation only is relied on is 72 hours or more and in such cooling the contraction of the gases within the 45 furnace inevitably causes an inrush of air with resultant oxidation of the metal rollers. It is estimated that by the time the furnace cools from 1600° F. to 800° F. the atmosphere within the furnace is at least 50% air. This amount 50 of oxygen in the furnace atmosphere is highly oxidizing.

In cooling the furnace by the means hereinabove described, the time interval of cooling may be lowered to from 5 to 6 hours by thermostatically controlling the rate of water flow through the cooling means to maintain a temperature in the returning gas of about 300° F. The fan means insures a substantially constant volume of gases at 300° F. temperature feeding into the furnace 1 at a positive pressure which prevents the leakage of air into the furnace during the cooling period. This eliminates entirely the deleterious effects of oxygen on the heated rollers during the cooling period and also shortens the 55 cooling period to a relatively small period as compared with the normal cooling period.

Having broadly and specifically described the present invention it is apparent that many modifications and departures may be made therein 70 without departing from the nature and scope thereof and all such modifications and departures are contemplated as may fall within the scope of the accompanying claims.

What I claim is:

75 1. In combination with an elongated furnace

provided with inlet and outlet openings adjacent each end of the furnace, and with means to heat the same with hot gaseous products of combustion, and with flue outlets at each end of the furnace adjacent said inlet and outlet openings, 5 and with means to regulate the proportionate distribution of gases exhausted through each flue outlet, means to cool said furnace when said heat supply means is shut off, said means comprising a cooling chamber and means to exhaust the hot 10 gases of combustion remaining in the furnace from one end of the furnace into said cooling chamber and to return the cooled gases to the opposite end of the furnace under a pressure at least sufficient to prevent the inflow of air 15 through said inlet and outlet openings.

2. In an elongated furnace having inlet and outlet openings in opposite ends, means to supply hot gases of combustion to said furnace to heat the same, and means to exhaust said gases from 20 opposite ends adjacent said inlet and outlet openings, said means including separate exhaust flues leading to a stack with damper means in each said flue to proportionately distribute the stack draft to said flues, means to facilitate the cooling 25 of said furnace and to prevent the inflow of air through said inlet and outlet openings when said heat supply means is shut off, said means comprising a cooling chamber, and fan means to exhaust the hot gases of combustion from one end 30 of said furnace through said flue adjacent the said end into said cooling chamber and thence under pressure back to the other end of the furnace through the other said flue.

3. In combination with an elongated furnace 35 having inlet and outlet openings in opposite ends, exhaust flues adjacent each said opening, damper means to regulate the flow of gases in each said flue, and means to supply hot gases of combustion to the furnace to heat the same, means to 40 facilitate the cooling of said furnace and to prevent the inflow of air through said inlet and outlet openings during the cooling of said furnace when the said heat supply means is shut off, said means comprising a gas cooling means, a by-pass 45 conduit communicating with each said exhaust flue on the furnace side of said damper means, an exhaust fan located in said conduit to withdraw gases from one end of said furnace through the said flue adjacent said end and to feed the same 50 under pressure through said gas cooling means into said other flue and back to the other end of the furnace.

4. In combination, an elongated furnace having inlet and outlet openings in opposite ends, 55 means to supply hot gases of combustion at spaced intervals over substantially the entire length of the furnace, means to convey articles to be treated through the furnace, a stack, a gas exhaust flue opening into one end of said furnace 60 adjacent the inlet opening and communicating with said stack, a second gas exhaust flue opening into the opposite end of the furnace adjacent the outlet opening and communicating with the said stack, damper means to regulate the stack 65 draft, damper means in each said flue to regulate the proportionate distribution of said stack draft in each said flue, and means to cool said furnace when the said heat supply means is shut off, said means including a by-pass conduit connecting 70 the two said flues at a point intermediate the flue dampers and the furnace, a gas cooling means located in said by-pass conduit, and fan means to exhaust gases from the furnace through one said flue into said gas cooling means and thence

- into the other said flue and back to the said furnace under a pressure at least sufficient to prevent the inflow of air into the furnace through the said inlet and outlet openings.
5. A rail treating furnace comprising an elongated refractory lined chamber rectangular in cross-section having a width adapted to enclose a plurality of side spaced rails and a length adapted to enclose a plurality of end spaced rails, 5
10 inlet and outlet openings in opposite ends of the chamber adapted to permit the entry and exit of rails endwise into and out of said chamber, movable closure members for said end openings, a roller bottom in said chamber adapted to im-
15 part endwise motion to rails located thereon so as to conduct the rails from the inlet to the outlet opening of the chamber, means to supply hot gases of combustion to said chamber at spaced intervals along substantially the entire length of
20 the chamber, means to exhaust said gases from each end of the chamber, said means including means to regulate the relative proportions of said gases exhausted at each said end, and means to cool the interior of the furnace when the said
25 heating means is shut off, said means including means to exhaust the hot gases of combustion then in the furnace from one end of the furnace, means to cool said gases, and means to return the cooled gases to the opposite end of the furnace
30 under a pressure at least sufficient to prevent the inflow of air through the inlet and outlet openings.

6. A rail treating furnace comprising an elongated refractory lined chamber rectangular in cross-section having a width adapted to enclose a plurality of side spaced rails and a length adapted to enclose a plurality of end spaced rails, 5
10 inlet and outlet openings in opposite ends of the chamber adapted to permit the entry and exit of rails endwise into and out of said chamber, movable closure members for said end openings, a roller bottom in said chamber adapted to impart 10 endwise motion to rails located thereon so as to conduct the rails from the inlet to the outlet opening of the chamber, means to supply hot gases of combustion to said chamber at spaced intervals along substantially the entire length of 15 the chamber, means to exhaust said gases from each end of the chamber, said means including means to regulate the relative proportions of said gases exhausted at each said end, and means to cool the interior of the furnace when the said
20 heating means is shut off, said means including means to close off said exhaust means, means to draw all the gases from one end of the chamber, means to cool said gases, means to return the cooled gases for recirculation through the 25 said chamber and means to regulate the temperature and pressure of said cooled gases to provide a positive pressure within the furnace effective to prevent the inflow of air into said furnace through said inlet and outlet openings. 30

ALBIN G. WITTING.
